Attorney.

UNITED STATES PATENT OFFICE.

WILLIAM E. WHITE, OF CLIFTON FORGE, VIRGINIA.

MECHANICAL MOVEMENT.

Application filed September 3, 1924. Serial No. 735,639.

To all whom it may concern.

Be it known that I, WILLIAM E. WHITE, a citizen of the United States, residing at Clifton Forge, in the county of Alleghany and State of Virginia, have invented a new and useful Mechanical Movement, of which the following is a specification.

This invention aims to provide novel means whereby, through a system of compound levers, motion may be transmitted from a source of power to a point of force application. The invention aims, further, to provide novel means for maintaining a balance in the leverage system, and to provide novel means for operating pawls whereby motion is transmitted to a rotary member.

It is within the province of the disclosure to improve generally and to enhance the utility of devices of that type to which the invention appertains.

Although a preferred form of the invention has been shown, it will be understood that any person, working within the scope of what is claimed, may make changes and alterations, without departing from the spirit of the invention.

In the drawings:—Figure 1 shows in top plan, a device constructed in accordance with the invention; Figure 2 is an elevation showing the main and auxiliary levers; Figure 3 is a side elevation wherein parts have been omitted; Figure 4 is a side elevation disclosing the complete device; Figure 5 is an elevation showing the pawls and attendant parts, portions being in section; Figure 6 is a section on the line 6—6 of Figure 5; Figure 7 is a sectional top plan disclosing the mounting of the main and auxiliary levers, and the connections therebetween; Figure 8 is a sectional view of the lever mechanism and its mounting, most parts appearing in elevation; Figure 9 is an end elevation of the structure delineated in Figure 8, parts being in section.

The numeral 1 marks a foundation carrying a pedestal 2 provided with an upstanding support 3. An auxiliary lever 4 is provided and carries a fulcrum piece 5 resting on the support 3. A fulcrum rod 6 is mounted in the pedestal 2 and passes through the inner end of the auxiliary lever 4, the same having arcuate slots 7 which permit the auxiliary lever to move with respect to the rod 6. A main lever 8 is mounted at one end to swing on the fulcrum

rod 6. A pivot element 9 connects the intermediate portion of the lever 8, as shown in Figure 7, with the inner end of the lever 4. As thus far described, the device comprises an auxiliary lever 4 fulcrumed intermediate its ends at 5, a main lever 8 fulcrumed at one end, as at 6, between the fulcrum 5 of the auxiliary lever 4 and one end of the auxiliary lever, and a pivotal connection 9 between the intermediate portion of the main lever 8 and said end of the auxiliary lever. If, through the instrumentality of an operating means 10 of any desired sort, the outer end of the lever 8 is swung in the direction of the arrow A in Figure 2, the outer end of the main lever 4 will be swung in the direction of the arrow B, the effect of the lever 8 on the lever 4 being compounded, owing to the construction hereinbefore described.

The numeral 11 designates a bell crank lever fulcrumed at 12 on the outer end of the auxiliary lever 4 and including a long arm 14 and a short arm 15. The long arm 14 of the bell crank lever 11 extends backwardly above the auxiliary lever 4, the short arm 15 extending downwardly with respect to the lever 4. Brackets 16 are pivoted at 17 to the auxiliary lever 4 on one side of the fulcrum 3—5 of said lever, the upper end of a connection 18 being mounted at 19 on the brackets 16 intermediate the ends thereof, the lower end of the connection 18 being mounted on the pivot element 9 which is located in the inner end of the auxiliary lever 4. Bell crank levers 20, in the form of plates, are mounted to swing on the fulcrum rod 6 and are pivotally connected at 21 with the brackets 16, the bell crank levers 20 being slotted to receive the connection 21 to permit relative movement between the parts 16 and 20, the lower ends of the bell crank levers 20 being pivoted at 22 to an approximately horizontal yoke 23 carrying a transverse connection 24 received in elongated slots 25 in links 26 which are pivoted at 27 to the lower ends of the short arm 15 of the bell crank lever 11. An inner radius arm 28 and an outer radius arm 29 are mounted intermediate their ends for swinging movement on the fulcrum rod 6, as disclosed in Figure 6. A connection 30 is pivoted at one end, as at 31, to the arm 15 of the bell crank lever 11, a connection 32 being pivoted at 33 to the arm 15 of the bell crank lever. The connection 30 is pivoted at 34

to the arm 28, and the connection 32 is pivoted at 35 to the arm 29. An operating pawl 36 is pivoted at 37 to the arm 28, and an operating pawl 38 is pivoted at 39 to the arm 29. Although the machine may be used to transmit power for any desired purpose, the pawls 36 and 38 are shown as cooperating with a ratchet wheel 40 connected to a drum 41 to rotate therewith, the drum being journaled on a support 42, and it being presupposed that the power is to be applied to a weight 43 carried by a flexible element 44 wound about the drum 41. A counterweighted back stop pawl 45 cooperates with the ratchet wheel 40 and is pivoted intermediate its ends on the fulcrum rod 6.

In practical operation, when swinging movement is imparted to the main lever 8, through any suitable instrumentality shown at 10, swinging movement will be imparted to the auxiliary lever 4 in the way hereinbefore described, a compound leverage being afforded. The bell crank levers 20 will be operated, and the yoke 23 and the links 26 will swing the bell crank lever 11 on its fulcrum 12, the connections 30 and 32 swinging the arms 28 and 29, the pawls 36 and 38 rotating the ratchet wheel 40 and the drum 41, the flexible element 44 being reeled on the drum, and the weight 43, for example, being lifted. If at any time the load exceeds the strength of the machine, the bell crank lever 11 will be tilted by means of the pawls 36 and 38, the arms 28 and 29 and the connections 30 and 32, the element 24 of Figure 8 and the links 26 having relative movement, owing to the presence of the elongated slots 25 in the links.

When the left hand end of the lever 4 in Figure 4 moves downwardly, the long weight arm 14 of the bell crank lever 11 will tend to swing downwardly at its right hand end, the links 26 tilting the bell crank levers 20 and causing a thrust to be exerted on the pivot element 9 in the inner end of the lever 4, through a train of elements including the brackets 16 and the connection 18, the result being that the levers 4 and 8 are always balanced, that is, they will remain in any position in which they may have been stopped, assuming, of course, that the machine, is judiciously proportioned.

Having thus described the invention, what is claimed is:—

1. In a device of the class described, an

auxiliary lever fulcrumed intermediate its ends, a main lever fulcrumed at one end between the fulcrum of the auxiliary lever and one end of the auxiliary lever, a pivotal connection between the intermediate portion of the main lever and said end of the auxiliary lever, means for applying power to the other end of the main lever, a bell crank lever fulcrumed on the other end of the auxiliary lever and including a weight arm 60 overhanging the auxiliary lever, the bell crank lever comprising a short arm, a ratchet wheel supported for rotation, a pawl 65 coacting with the ratchet wheel, a swinging arm whereunto the pawl is connected, means 70 for connecting the swinging arm to the short arm of the bell crank lever, and means for swinging the bell crank lever from the main and auxiliary levers.

2. A device of the class described, constructed as set forth in claim 1, and further characterized by the fact that the last-specified means embodies a second bell crank lever having a fixed fulcrum, means for connecting the second bell crank lever with the 75 main lever, and a connection between the second bell crank lever and the short arm of the first-specified lever.

3. In a device of the class described, an auxiliary lever fulcrumed intermediate its 80 ends, a main lever fulcrumed at one end between the fulcrum of the auxiliary lever and one end of the auxiliary lever, a pivotal connection between the intermediate portion of the main lever and said end of the auxiliary 85 lever, means for applying power to the other end of the main lever, means for transmitting power from the other end of the auxiliary lever, a bell crank lever fulcrumed on the last-specified end of the auxiliary lever 90 and including a short arm, and a long weight arm overhanging the auxiliary lever, and means connected with the short arm of the bell crank lever for transmitting a 95 thrust on the pivotal connection due to the weight of the long arm of the bell crank lever.

In testimony that I claim the foregoing as my own, I have hereto affixed my signature in the presence of two witnesses.

WILLIAM E. WHITE.
